UNITED STATES PATENT OFFICE

DAVID P. CUMMINGS, OF NEWTON CENTER, MASSACHUSETTS

FLEXIBLE SHEET MATERIAL

Application filed June 6, 1927. Serial No. 196,771.

This invention relates to a novel flexible sheet material and the process of producing the same.

One of the objects of the invention is to provide a flexible sheet material in the nature of a leather substitute having a flexible, but relatively inelastic woven body presenting a surface which may be compared to the grain of the leather with interengaging massed fibres woven in said body and projecting from the opposite side, and the whole impregnated throughout with a permanently flexible binder, the material being such that the reverse face formed by the interengaged fibres is comparable to the grain side of leather.

A further object of the invention is to provide a double face sheet material comprising parallel webs of fabric spaced apart by relatively movable fibres woven into said webs and impregnated throughout with a permanently flexible binder, thereby producing a product which may be considered as comparable to a double face leather.

A further object of the invention is to provide a double face material comprising parallel webs of fabric connected by a pile common to both webs and impregnated throughout with a permanently flexible binder, preferably rubber, compacted, and vulcanized under pressure, to produce a material comparable to leather having a grain surface upon each side.

A further object of the invention is to provide a material of the character described having a coating layer of preferably vulcanized material which may be embossed or grained to simulate leather or leather composition.

A further object of the invention is to provide a coated material of this character in which the coating may be channeled in such a manner that the material may be used as welts for shoes.

In short, the object of the invention is to provide a novel waterproof sheet material of great flexibility, strength and durability, which may be employed in various arts as leather substitutes or rubber substitutes.

The invention further relates to a process

of producing articles of the character above described.

Other objects and features of the invention will more fully appear from the following description and the accompanying drawings and will be particularly pointed out in the claims.

In the drawings:

Fig. 1 is a view in perspective of a flexible double face sheet material comprising webs of fabric spaced apart by a pile common to both webs and impregnated with a permanently flexible binder and compacted;

Fig. 2 is an edge view upon an enlarged scale of a double pile fabric comprising upper and lower parallel webs of fabric connected by a common pile;

Fig. 3 is a view in perspective of the double face sheet material illustrated in Fig. 1 having surface coatings applied thereto;

Fig. 4 is a view showing a pile fabric impregnated with a permanently flexible binder and having secured to the pile face thereof a coating layer of a substance adherent to the impregnating binder;

Fig. 5 is an edge view of two pile fabrics with the piles thereof presented toward each other;

Fig. 6 is an edge view of the pile fabrics illustrated in Fig. 5, with the piles thereof interengaged and impregnated throughout with a permanently flexible binder;

Fig. 7 is an edge view of a single pile fabric impregnated with a permanently flexible binder and compacted to cause permanent interengagement of the binder-impregnated fibres; and,

Fig. 8 is a perspective view of a section of welt comprising a double face fabric having a surface layer channeled to receive the stitches and showing the manner in which the channel may be formed.

The invention herein relates to the production of a flexible sheet material formed by impregnating a pile fabric having a woven body with pile fibres woven therein with a permanently flexible, preferably water-repellent, binder. Preferably the sheet material is made double faced by placing one pile of fabric upon another with the piles interen-

gaged, or by providing a double pile fabric comprising two parallel woven webs connected by a common pile. In either case the material is impregnated throughout with a 5 permanently flexible binder and thereafter compacted to produce a relatively thinner sheet of material than the pile fabric or fabrics before impregnation.

The sheet material thus constructed is characterized by extreme flexibility by virtue of the fact that the fibres of the pile, which are interposed between the woven faces thereof, permit relatively free movement of the woven webs with respect to each other, while 15 the impregnated pile fabric binds the woven webs firmly but flexibly together.

Any suitable permanently flexible binder which can be reduced to sufficient thinness properly to impregnate the material throughout 20 may be employed.

The preferred method of producing the material consists in thoroughly impregnating the pile fabric, or preferably pile fabrics, in which the piles are interengaged, or a 25 double face pile fabric having a common pile, with a suitable vaporizable cementitious liquid, such as latex, pyroxylin, or resinous composition, thereafter permitting or causing vaporization of the volatile content of 30 the liquid, and then compressing the material to produce a relatively thin sheet in which the pile or fibres, as well as the web or webs of the sheet, are thoroughly impregnated and compacted.

35 Preferably a vulcanizable material is employed as a binder. Such impregnating material desirably is pure rubber produced by impregnating the material thoroughly with latex. By the employment of latex the 40 fibres are impregnated and coated with rubber which can be readily vulcanized under heat and pressure. This impregnating material, which also permeates the web or webs of fabric, is capable of adherence to, or uniting 45 homogeneously with, a coating of rubber, rubber composition, or other coating which may be so treated as to either resemble rubber or imitation leather.

The coating may be applied by spreading, 50 or in sheet form, in either case under suitable pressure as is well known in the art and may be vulcanized in any well known manner. The flexible sheet material may be produced in accordance with my invention from various 55 types of pile fabric. The construction illustrated in Fig. 1 comprises a double face pile fabric which consists of an upper woven web 1 and a lower woven web 2 having a common pile 3. The structure of this double pile fabric is more particularly illustrated in Fig. 60 2 in which the webs of fabric are shown as separated by a pile common to both fabrics formed by threads extending through the upper and lower webs perpendicular thereto and spacing the webs apart. This double

pile fabric is commonly produced in the manufacture of pile fabric and the common pile cut or split intermediate of the webs to provide two webs of fabric having a pile extending from one face thereof. This desirably is 70 the material which is employed in the production of the present impregnated sheet material. When this pile fabric is impregnated and subjected to pressure the pile 3 is compacted down, as illustrated in Fig. 1, and the 75 fibres of the pile are permanently, but flexibly held together by the binder.

The binder material should be of a character to be adherent to a suitable coating layer. In Fig. 3 a flexible sheet material is 80 illustrated which comprises the impregnated and compacted double pile fabric, such as that illustrated in Fig. 1, provided with surface coating 4 and 5 of flexible water-repellant material which is adherent to, or coherent with, 85 the binder, such for example as a rubber composition where latex, or other impregnating material of rubber composition is employed.

Fig. 4 illustrates a web of fabric 6 having 90 a pile 7 impregnated with a suitable, permanently flexible, binder, such as rubber produced from latex, with a surface layer 8 of rubber, rubber composition, or other suitable material adherent to the binder compressed thereupon.

Fig. 5 illustrates two separate pile fabrics, the upper fabric having a web 9 and a pile 10, while the lower layer comprises a web 11 and a pile 12. In the production of the fabric herein described these two pile fabrics may be compressed together so that the piles 10 and 12 thereof will be interengaged or interlaced, while the webs 9 and 11 present upper and lower faces of the material, the whole 105 being impregnated, as before stated, with a suitable, permanently flexible, binder preferably having water-repellant characteristics.

In Fig. 7 a modified form of the invention 110 is illustrated which comprises a pile fabric having a woven web 13 and a pile 14, the whole being thoroughly impregnated with the binder, and compressed, to cause interengagement and interlacing of the fibres of the pile. This also presents a material which 115 is analogous to leather, the woven face of the pile corresponding to the grain surface of the leather, while the interlaced fibres correspond in effect to the flesh side of the leather.

The flexible sheet material, whether single 120 face as illustrated in Fig. 7, or double face as illustrated in Figs. 1, 3 and 6, have the characteristic "break" of leather and are exceedingly flexible. This sheet material is 125 adapted to be employed in various arts for many of the purposes for which leather, or rubber sheet material is used. The sheets are permanently flexible and are of extreme tenacity, being practically incapable of being torn in any direction. They are equally flex- 130

ible in all directions and have very little elasticity in the direction of the length or the width of the sheet because of the woven character of the webs of the pile fabric.

5 The utility of the material covers so wide a range that it seems useless to designate instances in which it may be employed. One of the uses, however, to which it may be readily adapted is in the production of welts for 10 shoes. In such case the single, or preferably the double, face material is provided with a surface coating and a channel formed in the coating in proximity to the edge thereof. A desirable form of welt is shown in Fig. 8 15 which illustrates a double pile fabric such as that shown in Fig. 3, the surface layer 4 being provided with a channel 15 extending longitudinally thereof in proximity to one of the edges of the strip of material. A channel 20 of this character can be readily formed during the compacting of the material by impressing a half-round rod 16 into the surface layer 4 at the time the layer is applied and vulcanized upon the surface of the impregnated 25 sheet material. When this welt is stitched to the shoe the stitches will lie within the channel 15. The stitches will not only pass through the woven webs of the material, but also through the impregnated pile 30 which intervenes between the woven layers, thus producing an anchorage for the stitches which is superior to that of any known material with which I am familiar.

It has been found that the sheet material 35 herein described can be repeatedly stitched through along the same line without tearing or appreciably weakening the strength of the material.

The strength of the material provided by 40 the woven webs, the connecting pile and the impregnation with the permanently flexible binder, is adapted to many uses where excessive strain or wear is imposed upon the material.

The term "pile fabric" is used herein in a broad sense as including any fabric having freely movable fibres or threads extending from a face thereof.

While latex has been described as the preferred impregnating binding material, it will be readily understood that other substances or compositions may be employed, such as pyroxylin, or pyroxylin composition, or other resinous or gummy substances capable of impregnating the material throughout and of providing a permanently flexible binder. It will, therefore, be understood that the particular disclosure of the present invention is of an illustrative character and is not restrictive 55 of the use of other impregnating materials, or of other fabrics which present a surface having relatively movable fibres or threads anchored in the web and projecting from a face thereof.

60 C5 Having thus described the invention, what

is claimed as new, and desired to be secured by Letters Patent, is:

1. A double face sheet material comprising parallel webs of pile fabric spaced apart by compacted pile fibres lying in intermingled 70 angular relation to the planes of said webs and impregnated throughout with a permanently flexible water-repellant binder.

2. A double face sheet material comprising parallel webs of pile fabric spaced apart by compacted pile fibres lying in intermingled 75 angular relation to the planes of said webs, impregnated throughout with a permanently flexible binder, and provided with a surface coating adherent to said impregnating 80 binder.

3. A double face sheet material comprising parallel webs of pile fabric spaced apart by compacted pile fibres lying in intermingled 85 angular relation to the planes of said webs, impregnated throughout with a vulcanized rubber and having a surface layer of vulcanized rubber.

4. A flexible sheet material comprising a web of pile fabric having a woven body with 90 pile fibres woven therein and compacted to lie in intermingled angular relation to the plane of said web impregnated throughout with a permanently flexible water-repellant material and having a surface coating ad- 95 herent to the impregnating material.

5. A flexible sheet material comprising a web of pile fabric having a woven body with 100 pile fibres woven therein and compacted to lie in intermingled angular relation to the plane of the web and impregnated throughout with vulcanized rubber and having a surface coating of vulcanized rubber coherent with said impregnating rubber and adherent to said pile fibres.

In testimony whereof, I have signed my name to this specification.

DAVID P. CUMMINGS.
